Attorney, Agent, or Firm—Price, Heneveld, Cooper, DeWitt & Litton

[57] CLAIM

The ornamental design for a seating unit, as shown and described.

DESCRIPTION

FIG. 1 is a front perspective view of a seating unit of the present invention;

FIG. 2 is a left side elevational view thereof, the right side being a mirror image;

FIG. 3 is a front elevational view thereof;

FIG. 4 is a top plan view thereof; and,

FIG. 5 is a rear elevational view thereof.

The dashed lines in FIGS. 1-5 are included to show the environment of the illustrated designs, but do not form a part of the present invention.
